US00D925849S

(12) **United States Design Patent** (10) **Patent No.:** **US D925,849 S**
(45) **Date of Patent:** **** Jul. 20, 2021**

(54) **ELECTRIC CLEANING DEVICE**

(71) Applicant: **SHENZHEN JASHEN TECHNOLOGY CO., LTD.**, Shenzhen (CN)

(72) Inventors: **Zhi-Chang Liu**, Shenzhen (CN); **Xiao-Ming Zhang**, Shenzhen (CN); **Jian-Xin Xi**, Shenzhen (CN)

(73) Assignee: **SHENZHEN JASHEN TECHNOLOGY CO., LTD.**, Shenzhen (CN)

(**) Term: **15 Years**

(21) Appl. No.: **29/704,601**

(22) Filed: **Sep. 5, 2019**

(51) LOC (13) Cl. **15-05**

(52) U.S. Cl.

USPC **D32/34**

(58) **Field of Classification Search**

(57) **CLAIM**

The ornamental design for an electric cleaning device, as shown and described.

DESCRIPTION

FIG. 1 is a perspective view of an electric cleaning device showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the electric cleaning device where an electric mop is separated from a base of the electric cleaning device.

The broken lines illustrate portions of the electric cleaning device that form no part of the claimed design.

1 Claim, 6 Drawing Sheets
